(57) **CLAIM**

The ornamental design for a pharmaceutical cap, as shown
and described.

DESCRIPTION

FIG. 1 is a top, front and right side perspective view of a
pharmaceutical cap of the claimed design;
FIG. 2 is a front elevation view thereof;
FIG. 3 is a right side elevation view thereof;
FIG. 4 is a back elevation view thereof;
FIG. 5 is a left side elevation view thereof;
FIG. 6 is a top plan view thereof; and,
FIG. 7 is a bottom plan view thereof.
Any broken line illustration of the environmental structure in
the drawing is not part of the claimed design.

1 Claim, 4 Drawing Sheets

FIG. 1

*FIG. 2**FIG. 3**FIG. 4**FIG. 5**FIG. 6*

FIG. 7
